UNITED STATES PATENT OFFICE.

CORNELIUS LEONHARD ROTHEUDT, OF WALHEIM, NEAR AACHEN, GERMANY.

GRAMOPHONE-RECORD.

1,046,650.

Specification of Letters Patent. Patented Dec. 10. 1912.

Application filed December 26, 1911. Serial No. 667,896.

To all whom it may concern:

Be it known that I, CORNELIUS LEONHARD ROTHEUDT, a subject of the Emperor of Germany, residing at Walheim, near Aachen, Germany, have invented certain Improvements in Gramophone-Records, of which the following is a specification.

When it is desired to play a gramophone record several times in succession, the stylus must each time be lifted and transferred from one end of the record groove to the other, the play being meanwhile interrupted. This is of great disadvantage particularly when marches and dances are to be repeated which repetition ought to be obtained without noticeable interruption in the play. This drawback is remedied by the present invention according to which the groove of a gramophone disk is made endless, the ends of the record groove being joined by a return groove carried in a parabolic curve across the turns of said record groove. The direction of the curve is naturally dependent upon the direction in which the disk turns and its form should be such as to guide the stylus with as little resistance as possible. Having once been started in the direction of the return groove, the stylus is easily guided through the same, and the part of the groove which crosses the turns of the record groove can therefore be narrowed sufficiently for preventing it having a detrimental effect on the record. The in-

terruption caused to the music while the stylus passes through the return-groove 35 will hardly be noticeable.

The invention is illustrated by way of example in the accompanying drawing by a plan of the improved gramophone disk.

In said drawings *a* is the disk and *b* 40 the spiral groove which contains the record. The ends of the groove *b* are joined by the return groove *c* which is carried in a parabolic curve across the turns of the groove *b*.

The record is started in the ordinary manner, and the stylus is automatically returned by the groove *c* to the starting end of the groove *b* so as to repeat the piece as long as the disk is kept in motion.

I claim:—

1. A gramophone disk comprising a return groove carried across the turns of the record groove and connecting the ends of the latter so as to return the stylus automatically to its starting position, substantially as set forth. 55

2. A gramophone disk comprising a return groove carried in a parabolic curve across the turns of the record groove and connecting the ends of the latter so as to return the stylus automatically to its starting position, substantially as set forth. 60
